UNITED STATES PATENT OFFICE.

FRANCIS A. RONNEBURG, OF CHICAGO, ILLINOIS.

DESIGN FOR AN AQUARIUM.

43,062.

Specification for Design.

Patented Sept. 24, 1912.

Application filed July 5, 1912. Serial No. 707,912. Term of patent 14 years.

To all whom it may concern:

Be it known that I, FRANCIS A. RONNEBURG, a citizen of the United States, residing at Chicago, in the county of Cook and State of Illinois, have invented a new, original, and ornamental Design for Aquariums, of which the following is a specification, reference being had to the accompanying drawing, forming a part thereof.

The figures are, Figure 1 a front elevation and Fig. 2 a top plan view of an aquarium, showing my new design.

The aquarium consists of a receptacle of

transparent material having a frame arranged on the front, and ornamentation on the back.

I claim,

The ornamental design for an aquarium, as shown.

In testimony whereof, I have hereunto signed my name in the presence of two subscribing witnesses.

FRANCIS A. RONNEBURG.
